Inventor,
John A. Smith

By Wm. H. Bates
Atty.

UNITED STATES PATENT OFFICE.

JOHN A. SMITH, OF WASHINGTON, DISTRICT OF COLUMBIA.

ELECTRIC SIGNAL FOR AUTOMOBILES AND OTHER VEHICLES.

1,375,540.

Specification of Letters Patent. Patented Apr. 19, 1921.

Application filed October 3, 1918. Serial No. 256,712.

To all whom it may concern:

Be it known that I, JOHN A. SMITH, citizen of the United States, residing at Washington, in the District of Columbia, have 5 invented certain new and useful Improvements in Electric Signals for Automobiles and other Vehicles, of which the following is a specification.

My invention has relation to improvements in electric signals adapted to be used 10 in connection with automobiles and similar vehicles, and the object of the invention is to provide suitable means for signaling, when necessary when the automobile is in 15 use.

With these ends in view the invention consists in the novel construction, arrangement 20 and combination of the several parts as will be hereinafter more particularly and in detail described and the asserted novelty specifically claimed.

I have clearly and fully illustrated my invention in the accompanying drawings in 25 which Figure 1 represents a plan view of a representation of a human hand with the illuminating means positioned therein.

Fig. 2 represents a horizontal section taken on the line 2-2 of Fig. 1.

In the accompanying drawings to which 30 reference is had, A designates a representation of a hand, which is formed of a hollow body of some transparent material.

B designates a multiple number of incandescent lamps located one within each finger, 35 the thumb and palm of the representation of the hand to which the current is fed, through the medium of conductor wires, in circuit with each lamp, and connected with

terminal posts carried by the wrist portions E of the hand. It is obvious that the outwardly projecting portions of these posts are adapted to be connected to feed wires (not shown), which lead from a battery in the vehicle, or on the person of the operator to provide the source of current necessary to 45 operate the lights.

C designates a multiple number of supports for supporting the lamps located below each lamp and engaging the plugs thereof as shown in Fig. 1 of the drawings. 50

This signal is particularly adapted for use at night, whereby the operator after connecting the terminal posts of the signal hand with the source of current, by extending the signal, which is brilliantly lighted by the arrangement of lights therein is able to notify approaching or following vehicles of a contemplated change of direction. 55

What I claim as new and desire to secure by Letters Patent is— 60

A signal of the class described comprising a hollow body formed of transparent material to simulate the appearance of a hand, a plurality of supports arranged one in each finger, the thumb and palm of the hand, an 65 electric light bulb positioned in each support, a current conducting wire having connection with each bulb, terminal posts carried by the wrist portion of the hand connected with the ends of said wire and adapted to receive an electrical current from an outside source whereby the lights will clearly illuminate the entire hand, as and for the purpose set forth. 70

In testimony whereof I affix my signature. 75
JOHN A. SMITH.
